UNITED STATES PATENT OFFICE.

MARY EDITH HODGE, OF WENONA, ILLINOIS.

APRON DRESS.

1,406,862.

Specification of Letters Patent. Patented Feb. 14, 1922.

Application filed October 8, 1919. Serial No. 329,198.

To all whom it may concern:

Be it known that I, MARY EDITH HODGE, a citizen of the United States, a resident of Wenona, in the county of Marshall and State 5 of Illinois, have invented new and useful Improvements in Apron Dresses, of which the following is a specification.

This invention relates to certain new and useful improvements in an apron, and among 10 other objects, it has to provide a reversible garment so that when the front thereof becomes soiled, the back may be turned around to serve as a new and clean front side.

A further aim of the invention is to minimize the cost of manufacture and material, 15 and facilitate the making of the same by constructing the apron of a one-piece top and a two-piece skirt portion, with a readily removable belt or sash for giving the necessary finished appearance to the garment.

In the drawing:

Figure 1 is a view of the apron from one side;

Figure 2 is a similar view of the reverse 25 side of the apron;

Figure 3 is a horizontal section on line 3—3 of Figure 1, through the skirt portion, and

Figure 4 is a vertical section on line 4—4 30 of Figure 1 through a sleeve;

Referring more in detail to the drawing, the top or waist portion is made from a single piece of material folded midway upon itself, as indicated at 2. This folded edge 35 2 has a semi-circular cut-out, which, when the folded material is opened, constitutes the neck opening 3 of sufficient size to permit the garment slipping on and off over the head of the wearer. The lower corners of 40 the folded top piece are cut away by substantially arcuate incisions, thereby accord- ing a cruciform shape to the blank or un- folded pattern. The outwardly and oppo- sitely extending sleeves 4 thus formed are stitched along their lower edges only, and the seams turned in, said stitching continu- ing downwardly to close up the sides of the waist portion.

The skirt portion 5 consists of two similar

pieces of material stitched together and their 50 seams turned in as depicted at 6 in Figure 3. The skirt portion is gathered at its upper edge and stitched to the lower edge of the waist portion at 7, and designed to encircle the garment at this stitched waist line, is a 55 detachable belt 8, which has its ends 9 hanging together to produce a neat and finished sash effect. The belt may be tacked or otherwise temporarily secured at two or more points, such as in front and back. 60 Therefore, when it becomes necessary or desirous to reverse the garment, the belt may be detached, turn about to bring the back of the belt to the formerly front, but now back side of the apron, and re-attached in 65 its new position.

The pockets 10 are positioned directly opposite to each other on the sides of the apron so as to be in convenient reach when the garment is worn in either position. 70

By reason of its three-piece construction, the manufacture of the apron may be carried on very expeditiously. The garment is practical and of a very advantageous design, being reversible, containing no biases and not 75 requiring any buttons, or fastening means of any kind.

What I claim is:

A reversible apron dress comprising a one-piece waist part of cruciform formed of a 80 folded piece of material having a neck opening in the line of fold and having oppositely extending sleeve portions, a skirt part formed of two similar pieces of material sewed together along their side edges, the 85 upper edges of the pieces of the skirt part being stitched to the lower free edges of the folded piece of which the waist part is formed, and a belt having its ends hanging downwardly and adjacent to each other, said 90 belt being removably tacked to the front and back of the apron to accommodate it to the reversibility of the apron and arranged over the stitching between the waist and skirt parts. 95

In witness whereof I have hereunto affixed my hand this 22nd day of September, 1919.

MARY EDITH HODGE.
